UNITED STATES PATENT OFFICE.

EARL W. ZIMMERMAN, OF SYRACUSE, NEW YORK.

ROLLER FOR CONVEYERS.

Application filed July 15, 1926. Serial No. 122,653.

This invention relates to conveyers such as are used for carrying articles from one place in a building to another and which comprises a runway of free rotating rollers 5 and it consists of means self contained with each roller for retarding the momentum of the roller and preventing idle spinning or rotating thereof.

The invention consists in the novel features 10 and in the combinations and constructions hereinafter set forth and claimed.

In describing this invention, reference is had to the accompanying drawings in which like characters designate corresponding parts 15 in all the views.

Figure 1 is a fragmentary perspective view of a conveyer embodying my invention.

Figure 2 is an elevation, partly broken away, and partly in section, of one of the 20 rollers.

Figure 3 is a cross sectional view through one of the rollers.

Figure 4 is a perspective view of a modified form of a conveyer embodying my invention.

Figure 5 is a view similar to Figure 2 of a form of a roller shown in Figure 4.

Figure 6 is a detail view of the means for stopping the momentum of the roller shown 30 in Figure 5.

As is well known to those skilled in the art, in carriers embodying rollers, the rollers after an article has passed over them continue to roll or rotate so that the succeeding articles 35 are passed along faster than and collide with the articles in front, and this happens whether or not the carrier is inclined or some of the rollers are power driven.

In some conveyers, attempts have been 40 overcome to prevent the acceleration of the movement of the articles by connecting up rollers at intervals with power or by putting various forms of friction brakes on the rollers.

Neither of the foregoing ways of retarding 45 the momentum of the rollers is entirely satisfactory.

My invention consists of a conveyer in which the rollers have self contained means 50 for retarding their momentum.

In the drawings, 1 designates the frame of the general type of conveyer embodying my invention, and 2 is the series of rollers, the rollers being here shown as mounted on axles 3 supported in the frame 1. The axles are 55 stationary and anti-friction bearings 4 are interposed between the heads at opposite ends of the rollers and the axles 3. The axles are here shown as mounted in slots 5 in the frame 1 and hence capable of a sliding movement lengthwise of the conveyer.

The means for preventing or retarding the momentum of the roller comprises an eccentric weight fixed within the roller, this weight being designated 7 and preferably extending 65 the length of the roller. Obviously, the weight inside of the roller will always tend to hold the roller so that the weight is below the axes of the roller and hence to retard the momentum or stop the rotation of the roller 70 after the article being conveyed has passed over the roller, it being understood that such article causes the roller to rotate.

In Figures 4, 5 and 6, a modified form of such momentum retarding means is shown 75 in which the weight 8 for retarding the momentum of the roller is carried by an arm 9 mounted on the axle 10, the axle 10 and the roller 11 being rotatable as a unit.

In this form of my invention, anti-friction 80 bearings 12 are interposed between the axle 10 and the frame 13 of the conveyer. Also, the frame 13 is provided with suitable guards 14 which shield the weights of the rollers and prevent them fouling on a person or thing 85 near the conveyer.

This conveyer is obviously, particularly advantageous in that the means for retarding each roller is self contained with the roller and independent of the frame or any other 90 roller or thing.

What I claim is:

A conveyer comprising a series of rollers, each roller having an eccentric weight on one side of its axis.

In testimony whereof, I have hereunto signed my name, at Syracuse, in the county of Onondaga, and State of New York, this 1st day of May, 1926.

EARL W. ZIMMERMAN.
